UNITED STATES PATENT OFFICE.

JEROME W. LEARY, OF PLAINFIELD, NEW JERSEY, ASSIGNOR TO THE ALUMINUM PLATE AND PRESS COMPANY, OF SAME PLACE AND NEW YORK, N. Y.

COUNTING DEVICE FOR PRINTING-PRESSES.

SPECIFICATION forming part of Letters Patent No. 657,781, dated September 11, 1900.

Application filed June 5, 1900. Serial No. 19,108. (No model.)

To all whom it may concern:

Be it known that I, JEROME W. LEARY, a citizen of the United States, residing at Plainfield, in the county of Union and State of New Jersey, have invented certain new and useful Improvements in Counting Devices for Printing-PresSES, of which the following is a specification.

The object of my invention is to provide a counting device for printing-presSES or other machines which is adapted to be operated by the movement of a part of the machine in one direction and allow the movement of said part of the machine in the opposite direction without injury to the counting device.

In the preferred application of my invention a counting device of any suitable construction is provided with a rock-arm arranged to be intermittently engaged by a pin or lug carried by a rotating part of the machine to which it is applied. The operating rock-arm is prepared with a knuckle-joint, so as to register the movement of the part in one direction and at the same time allow movement of the said part in the reverse direction without injury to the counting mechanism. The two parts of the counter-operating arm are pivotally connected and formed with engaging shoulders to constitute the knuckle-joint. A spring is preferably mounted upon one of the sections of the arm, so as to engage the other section and yieldingly hold the two sections in the desired normal relation.

In order that my invention may be fully understood, I will first describe the same with relation to the accompanying drawings and will afterward point out the novelty more particularly in the annexed claims.

In said drawings, Figure 1 is a side elevation of part of a printing-press having a counting device applied thereto embodying my invention. Fig. 2 is a detail view of the knuckle-jointed operating-arm of the counting device.

For the purpose of illustrating my invention I have shown it applied to a counting device arranged in accordance with the invention of Edward C. Seymour, who filed an application for patent thereon May 22, 1900, Serial No. 17,567, said invention consisting of

a device for throwing a counting device into or out of operation.

1 indicates a part of the press-frame of a rotary printing-press.

2 is the plate or form cylinder, journaled 55 in frame 1.

4 is the impression-cylinder, mounted upon the shaft 5, which is journaled in eccentric-bearing bushings 6, said bushings being in turn journaled in the machine-frame 1 and 60 formed with integral arms 7, which are connected with any suitable operating mechanism, such as toggle-links 8 9, by which they are operated for moving the impression-cylinder into and out of operative relation with 65 the plate or form cylinder.

10 is a counting device of any approved construction. This device is mounted to slide in a bracket 11, secured to the press-frame and formed with guide-flanges 12. 70

13 is a link connecting the counting device with one of the eccentric-bearing bushings 6. This last-described device—viz., the connecting-arm between the counting device and the eccentric bearing—does not comprise a part 75 of any invention, and I do not limit my device to a machine having this particular form of construction.

16 17 are inner and outer sections or parts of the operating rock-arm of the counting 80 mechanism. The inner section 16 is suitably connected with the internal operating mechanism of the counting device 10, so that every complete stroke of the arm 16 17 will register one number in the counting device. The 85 outer end of the part or section 16 is formed with a beveled face or shoulder 16^a, while the inner end of the part or section 17 is formed with a yoke 18, which straddles the outer end of part 16 and is pivotally connected therewith by a pivot-pin 19. The inner face of the yoke 18 of the part 17 is beveled at 18^a to correspond with the shape of the shoulder 16^a of the part 16, so that when the parts 16 17 are arranged in line, as shown in full lines 95 in Fig. 1, the beveled faces of the two parts will lock and form an arm which is rigid to downward pressure upon section 17.

25 is a leaf-spring set into a notch 26 of the part 17 and extended over to the part 16, 100

which it engages. When the parts 16 17 are in operative position—that is, in line—the spring 25 engages the under face of the part 16 and holds said part in this position with a yielding pressure. When, on the other hand, the outer section or part 17 is moved upwardly with relation to part 16, the spring 25 will engage the beveled face 16^a on part 16 and hold the parts in this relative position, as shown in dotted lines in the drawings.

20 is a collar adjustably mounted upon the projecting end of the impression-cylinder shaft 5 by means of set-screws 21. The collar 20 supports a pin, lug, or screw 22, which in its rotation engages the counter-operating arm 16 and moves it downwardly and registers its revolution upon the counter.

It will be observed that when the machine is operating, the impression-cylinder being in operative relation to the form-cylinder, the pin, lug, or screw 22 will engage the outer part 17 of the counter-operating arm and depress it sufficiently to actuate the counter, the pin or lug 22 passing around out of engagement with the arm and allowing its spring mechanism inside of the counter to return it to normal elevated position in readiness to receive another stroke the next time the pin or lug 22 comes around. This is the normal operation of the device.

The value of my invention will be clear from the following observations: In case the impression-cylinder or other part which operates the counting mechanism is backed up or rotated in the reverse direction, so as to cause the pin or lug 22 to engage beneath the counter-operating arm, it will be clear that the operating-arm will break joint at the pivot 19, as above explained. If the operating-arm were formed in a single rigid piece, this backward movement of the impression-cylinder would break the counting mechanism.

ism. My invention is also important because it makes it possible to throw out of operation the counting mechanism while the press is printing the "dead" sheets or first lot of sheets which are passed through the press to test the register, the inking, and general operation of the press. With the common construction of sheet-counters for printing-presses these dead sheets are registered upon the counter, and unless the operator is particular in noting the indicators of the counter after he has finished printing these dead sheets and testing the machine he will not have an accurate count of the sheets printed. With my improved counter, however, the dead sheets are not counted, and an accurate count of the sheets printed for use is obtained.

Having thus described my invention, what I claim as new, and desire to secure by Letters Patent, is—

1. In a machine, the combination with a counting device, and a revolving shaft, of an actuating-arm for said counting device composed of two pivotally-connected parts, of a pin revolving with said shaft and adapted to engage said arm for the purposes of operating same while moving in one direction and throwing it out of operation while moving in the other direction as set forth.

2. In a machine, the combination with a counting device, a revolving shaft and a counter-actuating pin rotating with said shaft, of an actuating-arm for said counting device composed of two parts and having a knuckle-joint between said parts, and a spring attached to one of said parts and adapted to bear against the other of said parts, for the purposes set forth.

JEROME W. LEARY.
